UNITED STATES PATENT OFFICE.

HUGO C. GIBSON, OF NEW YORK, N. Y.

WHEEL.

Application filed June 14, 1916. Serial No. 103,635.

To all whom it may concern:

Be it known that I, HUGO C. GIBSON, a subject of the King of Great Britain, and a resident of New York city, county and State 5 of New York, have invented certain new and useful Improvements in Wheels, of which the following is a specification, reference being had to the drawings herein referred to, which are made a part hereof.

10 This invention relates to wheels, and more particularly to the means for securing the rim to the periphery of the wheel. Among the particular objects are to produce a simple and economical device of this 15 character, which will be most effective in securing the rim and avoid accidental dislodgment of any extraordinary strain.

While my invention may be embodied in various forms, its construction or design 20 may be made universal, that is, to fit a variety of all kinds and shapes of rims in connection with which it is likely to be used, the original form in which I have embodied it is shown in the accompanying drawings, 25 in which:

Fig. 1 is a section of wheel rim and securing device.

Fig. 2 is a side view showing the clamping device secured, and in dotted lines turned 30 for release.

Fig. 3 is a top view of one of the securing devices.

Fig. 4 is an elevation of Fig. 3.

Fig. 5 is a fragmentary section and elevation of modified detail of clamp shown 35 in engagement with the rim.

A is the felly, B is the felly-band, C is the demountable rim, D is the main member of the securing device, E is the second member 40 of the securing device, F is the means connecting the two parts of the securing device, G is the boat, g is a nut.

The main member D of the securing device, has a heel d engaging the side of the 45 felly, which may, however, be any peripheral portion of the wheel fixed with relation to the main portion of the wheel, and at the other end it has a toe or wedge-shaped projection d', the upper face of 50 which d' is inclined with respect to the felly-band B. The second member E of the clamping device has a surface e bearing on the surface d'', and at one end has a portion e'' adapted to engage the rim, which

preferably is at the up-turned side of the 55 rim at a point having a larger diameter than the minimum inside diameter of the rim. At the other end of E, which may be called the heel, I produce an enlargement e''' in the modified form shown in Fig. 5, 60 while in Fig. 4 the end e''' may be of uniform thickness. In either case the member E is adapted for engagement with the side of the rim preferably at two points, the one more or less under the rim and the other 65 point at the up-turned portion at the side.

The second part of the securing means E'', as shown in Fig. 5, has the enlarged projection e''', which I call the heel, with the object of having that end tapered so 70 that the pressure of the first member D of the securing device when being forced in, will tend to hold the second member E snugly against the rim and press it in laterally to maintain it in fixed relation with 75 the rim. The upper end of part D, namely, the flange d', moves when the securing portion slides on the bearing surface e in engagement with the surface d'' of the second member. The stud H secures the two members loosely together, being riveted to one and passing through a slot H in the other. As shown in Fig. 3, this slot is in the member E and is recessed as at h', so that the head of the rivet H will be flush with or 80 below the bearing surface e'''.

As shown at K, the aperture L in the member D is enlarged at one side so that when the clamp is loosened it may be withdrawn, so that the lip or wedge flange d' 90 clears the edge of the felly or fixed portion of the wheel, and the entire securing device can then be turned laterally, and will drop away, or can be forced towards the centre 95 of the wheel so that the sides of the securing means will not obstruct the removal of the rim laterally.

The clamps, however, may be so proportioned that the opening L will permit of sufficient movement so as to allow the rim 100 to be laterally displaced without interference.

In embodying my invention in a continuous wedge ring, that is, on a plurality of individual clamps or lugs, but one piece split 105 at only one point in its periphery, I may do so by having the fixed piece E of the clamp a split ring, and the other lugs or parts D

individual, or the part D may be continuous and the members E a plurality of separate pieces, or each of the parts E and D may be a split ring.

5 While my securing means in any of its various forms is inserted at one side, on the other side of the wheel periphery, and as shown in the accompanying drawings, the felly-band has a projecting ridge which engages the other side of the rim. This, however, may be modified in various ways. Individual stops or abutments may be used, or engaging ribs or collars under the rim, in any manner adapted to co-operate with my 10 securing device. The securing device may also be shaped in its parts so as to engage on one element, that is, along a circumferential element of the rim, or it may have two points of engagement, as illustrated in 15 the accompanying drawings, or so fashioned as to have a degree of surface contact to suit desired conditions.

Primarily, however, the secondary member E engages and retains a fixed position 20 laterally with respect to the rim and the wheel proper, in conjunction with the abutment engaging the other side of the rim,— and by engagement of the up-turned side will with perfect certainty prevent the lateral displacement of the rim over the securing device. With this the other member D of the securing device is afforded two obliquely disposed surfaces between which the wedge shaped end d' may be pressed, and 25 may be moved to any extent that becomes necessary in order to properly effect the locking of the rim. In other words, one portion of my clamp performs the function of absolutely preventing lateral displacement and the additional function of presenting in conjunction with the edge surface of the felly-band, a perfect seat for the wedge which effects the actual clamping. The co-operation of the parts is such that 30 the radial clamping is effected with certainty, because the flange of the member D presents a straight surface, so that it will be forced into position until the actual radial strain stops it, whereas some clamps for rims now in use will be prevented from moving 35 to the desired extent to create radial pressure, on account of the engagement on the up-turned side of the rim, thereby resulting in only lateral pressure of a greater degree, and not the perfect securing effect obtained by my invention.

The securing device may even be duplicated on opposite sides of the wheel. Many variations may be made in details of construction or dimensions, as well as material. In the preferred form the parts are made of metal of quality best suited for cheapness and strength and facility of manufacture.

Without confining myself to the particular form of constructions herein shown and

described, what I claim and desire to secure by Letters Patent is:

1. In combination in a wheel, a fixed peripheral element on the wheel so positioned as to form an abutment for the detachable 70 rim to prevent its movement in one direction, a plurality of two-part clamps disposed at spaced intervals about the periphery between the fixed wheel element and one side of the detachable rim, one of the parts of 75 each of said clamps adapted to engage the rim and the other part of each of said two-part clamps adapted to move laterally with respect to the fixed peripheral wheel element to cause the locking of said detachable 80 rim in position, and means for forcing the second part of each of said clamps laterally and for securing it in locking position.

2. In a wheel, a detachable rim, a peripheral fixed element on the wheel proper having a fixed abutment for engagement of the detachable rim when moved in one direction, a plurality of clamps disposed in spaced relation about the periphery between the fixed element and one edge of the detachable 90 rim, means for drawing one part of each of said clamps against said peripheral element, a bearing face on each of said clamps inclined to the peripheral surface of the fixed element on the wheel and a movable element 95 associated with each of said clamps slideable on said inclined bearing face and having its opposite face adapted to engage the detachable rim for the purpose of locking the same in position on the wheel. 100

3. In combination in a wheel, a tire rim securing means comprising a plurality of clamp elements in spaced peripheral position around the periphery of the wheel and movable laterally with respect to the wheel periphery, and a clamping block associated with each of said clamp elements and slideable thereon adapted to engage the rim on one side and means to force the engagement of said clamp elements whereby they remain immovable with relation to the wheel when said tire rim is secured. 110

4. A tire rim clamp having a bearing at one end adapted to engage a side of a fixed peripheral part of the wheel and having a 115 wedge-shaped flange at the other end adapted to be inserted between the periphery of the wheel and the over-hanging portion of the rim, a hole in said clamp, an abutment on the side of the wheel proper, means to move said clamp with relation to the peripheral portion of the wheel, and an enlargement on one side of the hole adapted to permit limited lateral movement of said clamp with relation to said abutment. 120

5. In combination in a wheel, a demountable rim, a fixed abutment for limiting the movement of said rim in one direction, a clamp adapted in the operation of securing said rim to force the rim in the direction of 130

its engagement with the abutment, said clamp comprising two parts having inclined engaging surfaces, whereby the operation of tightening said clamp to secure the rim is accomplished by the relative sliding of said two parts of the clamp, for the purpose described.

In testimony whereof I have signed my

name to this specification, in the presence of two subscribing witnesses, this 13th day 10 of June, 1916.

HUGO C. GIBSON.
